CLAIM

(51) **LOC (13) Cl.** **14-04**

We claim the ornamental design for a display screen or portion thereof with graphical user interface, as shown and described.

(52) **U.S. Cl.**

USPC **D14/485**

DESCRIPTION

(58) **Field of Classification Search**

FIG. 1 is a front view of a first image in a sequence for a display screen or portion thereof with graphical user interface showing our new design;

USPC D14/485-495

FIG. 2 is the second image thereof; and,

CPC H04M 1/72519-72561; G06F 15/0266;

FIG. 3 is the third image thereof.

G06Q 10/06; G06Q 10/109; G06Q 50/01;

The outermost broken lines in the figures show the display screen or portion thereof and form no part of the claimed design. The remaining broken lines depict portions of the graphical user interface that form no part of the claimed design.

H04L 51/32

The appearance of the graphical user interface sequentially transitions between the images shown in FIGS. 1-3. The process or period in which one image transitions to another forms no part of the claimed design.

See application file for complete search history.
